(57) **CLAIM**

The ornamental design for an in-tire sensor, as shown and described.

DESCRIPTION

FIG. 1 is a front and top perspective view of an in-tire sensor showing my new design.

FIG. 2 is a rear and bottom perspective view of an in-tire sensor.

FIG. 3 is a front view of an in-tire sensor.

FIG. 4 is a rear view of an in-tire sensor.

FIG. 5 is a left side view of an in-tire sensor.

FIG. 6 is a right side view of an in-tire sensor.

FIG. 7 is a top view of an in-tire sensor; and,

FIG. 8 is a bottom view of an in-tire sensor.

1 Claim, 8 Drawing Sheets
